UNITED STATES PATENT OFFICE.

JOHN HORN, OF KANSAS CITY, MISSOURI.

AUTOMATIC REVERSER.

1,257,352.

Specification of Letters Patent. Patented Feb. 26, 1918.

Application filed May 25, 1917. Serial No. 170,910.

To all whom it may concern:

Be it known that I, JOHN HORN, a citizen of the United States, residing at Kansas City, in the county of Jackson and State 5 of Missouri, have invented a new and useful Automatic Reverser, of which the following is a specification.

The present invention relates to a mechanism for automatically reversing the valves 10 or devices which control a furnace or the like, it being the object of the invention to provide a novel and improved automatic reversing mechanism for intermittently reversing the air and fuel valves of an open 15 hearth steel melting furnace, soaking pit, heating furnace, brick kiln, or the like, whereby the valves will be opened and closed at the proper intervals and without relying upon an operator to do this work, 20 as usual, and thus avoiding human mistakes.

Melting furnaces, brick kilns, and the like, generally require the reversal of the flames or fuel from one end or point to another, as well as the reversal of the air and 25 stack or flue valves. This is usually done manually, but it is not infrequently the case that the reversal is not made at the proper intervals, and furthermore, the attention of 30 the operator is required almost continuously during the operation of the furnace, whereas with the present mechanism, the attention of the operator is eliminated, and the reversal is accomplished automatically at 35 the proper intervals.

A further object of the invention is the provision of a mechanism of the nature indicated embodying a novel assemblage of the component elements, whereby to enhance the utility and efficiency of the 40 apparatus.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 45 within the scope of what is claimed without departing from the spirit of the invention.

The invention is illustrated in the accompanying drawings, wherein:

55 Figure 1 is a front view of the mechanism, portions being broken away, and the elec-

trical side of the mechanism being illustrated diagrammatically.

Fig. 2 is a diagrammatical view illustrating the valves. 60

Fig. 3 is a fragmental plan view showing some of the pressure fluid valves.

Fig. 4 is a fragmental detail illustrating a modification.

In the drawings, the numeral 1 designates 65 a fuel supply pipe through which gas, oil or other fuel is supplied to branch pipes 2 leading to the opposite ends of the furnace, kiln, or the like. The branch pipes 2 are alternately opened and closed by means of 70 suitable valves 3 and 4, one valve being closed while the other is open, and the valves being reversed at intervals, to change the supply of fuel from one end of the furnace to the other. 75

Between the valves 3 and 4 is a horizontal row of vertical cylinders 5, 6, 7, 8 and 9, it being understood that any suitable number of these cylinders can be used, according to the circumstances. The upper ends of 80 said cylinders have portions 10 bolted or otherwise fastened to a horizontal supporting bar or frame 11 and the lower ends of said cylinders have heads 12. Pistons 13 are slidable vertically within the cylinders 85 and have depending piston rods 14 extending through the heads 12. The piston rods 14 of the cylinders 5 and 6 can be connected to the air valves at one end of the furnace, and the piston rods of the cylinders 8 and 9 can be connected to the air 90 valves at the other end of the furnace, while the piston rod of the cylinder 7 can be connected to the flue or stack valves. The piston rods are connected by any suitable operative connections with the valves or devices, and since the present invention does not concern said connections or the common 95 valves or devices to which the piston rods are connected, they need not be illustrated or described in detail. Stop screws 15 are threaded downwardly through the upper ends of the cylinders and are adjustable to limit the upward movement of the pistons.

Three way fluid pressure or compressed 105 air valves 15, 16, 17—17', 18 and 19 are provided for the respective cylinders 5, 6, 7, 8 and 9, said valves being of similar construction, and are disposed in front of a horizontal fluid pressure supply pipe 20 which 110 is in turn in front of the cylinders. The pipe 20 has branches 23 connected to said

valves, and each valve is connected by a pipe 21 with the respective cylinder, each valve also having an exhaust port 22 opening into the atmosphere. The pipes 21 of the valves 15, 16, 17, 18 and 19 are connected to the lower portions of the respective cylinders 5, 6, 7, 8 and 9, while the pipe 21 of the valve 17' is connected to the upper portion of the intermediate cylinder 7. This cylinder 7 has the two valves 17 and 17', whereby the piston of this cylinder is moved by fluid pressure in both directions, while the pistons of the cylinders 5, 6, 8 and 9 are simply raised by fluid pressure, and moved downwardly by gravity, assisted by the movement of the devices to which the piston rods are connected.

The valves 3, 15, 16, 17, 17', 18, 19 and 4, are arranged in a horizontal line or longitudinal series, as seen in Fig. 1, and an oscillating member of each valve is provided exteriorly of the valve casing with an L-shaped or angular operating member 24 whose arms are arranged substantially at right angles with one another. These members 24 are oscillated back and forth at intervals for reversing the valves, as will presently appear.

A nut 25 travels upon a horizontal screw 26 arranged parallel with the series of valves, and having its terminals journaled in suitable bearings 27. The nut 25 is movable along guide rods 28 terminally attached to the bearings 27, and the nut 25 has a tappet member 29, which is preferably provided with a roller 30 for engaging the members 24, the roller 30 being movable under said members 24 in engagement with the arms thereof.

A reversible electric motor 31 is geared, by a worm and worm wheel or the like, to one end of the screw 26, and the operation of said motor at suitable intervals is controlled by any suitable clock 32, which has the shaft or arbor 33. The shaft 33 can be rotated once every hour, or can be so geared to the clock to be rotated at the desired speed. Disks 34 are mounted upon the shaft 33 and are insulated from one another, and have switch members 35 arranged alternately, to engage the respective contacts 36 and 37. Electrical current is supplied by the generator 38 or other suitable source of electrical energy, and switches 39 and 40 of any suitable sort, are arranged to be operated when the nut 25 reaches the ends of its movements in opposite directions. These switches 39 and 40 are connected by a link 41 or otherwise so that as one switch is closed, the other is opened, they being operated alternately. The switch 39 when closed, closes the circuit between conductors 42 and 43, the former being connected to one terminal of the generator 38 and one contact 36, and the latter being connected with one

terminal of the motor 31. A switch 40 serves to close the circuit between said terminal of the motor 31 and a conductor 44 which is connected to one contact 37 and the other terminal of the generator 38. The other contacts 36 and 37 are connected by a conductor 45 with the other terminal of the motor 31. The nut 25 carries U-shaped members 46 for operating the switches 39 and 40.

With the parts arranged as illustrated in Figs. 1 and 2, the nut 25 is at the left hand end of the screw 26 and the member 26 has opened the switch 39. The right hand arms of the members 24 are in depending position and the left hand arms project toward the left. Valve 3 is in open position so that the fuel can flow through the left hand branch 2, while the valve 4 is closed. Valves 15, 16 and 17 establish communication between the fluid pressure pipe 8 and lower portions of the cylinders 5, 6 and 7 so that the respective piston rods are raised for correspondingly moving the valves or parts to which they are connected. The valves 17', 18 and 19 connect the upper portion of the cylinder 7 and lower portions of the cylinders 8 and 9 with the ports 22 opening into the atmosphere, whereby the piston of cylinder 7 can move upwardly, while the pistons of cylinders 8 and 9 can move downwardly. After an interval of time, say fifteen or twenty minutes, one of the switch or bridging members 35 is moved into engagement with the contacts 36 to bridge the gap therebetween, the switch 40 having previously closed when the switch 39 opened. This closes a circuit including the generator 38, conductor 42, contacts 36, conductor 45, motor 31, switch 40 and conductor 44. The motor will therefore rotate in one direction, for so rotating the screw 26, in the corresponding direction, so that the nut 25 is moved toward the right. The member 29 is therefore carried under the members 24 in succession, and in contacting with the right hand depending arms of said members 24 will swing them toward the right, the left hand arms being swung downwardly to depending position. This reverses the valves 3, 15, 16, 17, 17', 18, 19 and 4 in succession. The valve 3 is therefore closed, and the valves 15, 16, and 17 now establish communication between the lower portions of the cylinders 5, 6 and 7 and the atmosphere, permitting the respective pistons to move downwardly. Valve 17' establishes communication between the pipe 20 and upper portion of the cylinder 7, whereby the respective piston is forced downwardly by pressure fluid, while valves 18 and 19 now establish communication between the pipe 20 and lower portions of the cylinders 8 and 9, whereby their pistons are forcibly raised. Valve 4 is opened to reverse the

flow of fuel to the other end of the furnace. When the nut 25 reaches the end of its movement to the right, the member 46 opens the switch 40, and closes the switch 39. Switch 5 40 being opened will open the circuit above described, thereby stopping the motor 31, after which the respective switch member 35 is moved away from the contacts 36. After another interval of time, the next 10 switch member 35 engages the contacts 37, as seen in Fig. 1, to close the circuit including the generator 38, conductor 42, switch 29, which is now closed, conductor 43, motor 31, conductor 45, contacts 37 and conductor 44. 15 The motor 31 is therefore rotated in the opposite direction as well as the screw 26, thereby moving the nut 25 to the left, and the members 24 will therefore be moved back to the position illustrated in Fig. 1, thereby 20 again reversing the valves and bringing them to the position first described. When the nut 25 reaches the end of its movement to the left, it opens the switch 39 and closes the switch 40, and the switch 39 being opened 25 stops the motor. The nut 25 is therefore moved in one direction and then in the other direction at the desired intervals, for reversing the valves automatically. Any suitable clock controlled circuit controlling device 30 can be employed for opening and closing the motor circuits at the proper intervals.

In the modification illustrated in Fig. 4, the screw 26^a has right and left hand threads, whereby it need only be rotated in one direction, the movement of the nut 25^a being reversed at the ends of the screw.

Having thus described the invention, what is claimed as new is:—

1. An automatic reverser, comprising a 40 series of cylinders, pistons in the cylin-

ders, a fluid pressure supply conduit communicating with the cylinders, valves in the conduit for controlling the fluid pressure supply, a traveler mounted for reciprocation before the cylinders, a tappet on 45 the traveler for successively operating the valves, mechanism for reciprocating the traveler, and, means controlled by the traveler for operating the reciprocating mechanism.

2. An automatic reverser, comprising a series of cylinders, pistons in the cylinders, a fluid pressure supply conduit communicating with the cylinders, valves in the conduit for controlling the fluid pressure supply, a 50 traveler reciprocable before the cylinders, a tappet on the traveler for successively operating the valves, means for reciprocating the traveler, a member depending from the traveler, and means controlled by the depending member for operating the reciprocating means.

3. An automatic reverser, comprising a series of cylinders, pistons in the cylinders, a fluid pressure supply conduit communicating with the cylinders, valves in the conduit for controlling the fluid pressure supply, a screw actuated traveler reciprocable past the valves, a tappet on the traveler for successively operating the valves, and means 65 controlled by the traveler for operating the screw.

In testimony that I claim the foregoing as my own, I have hereto affixed my signature in the presence of two witnesses.

JOHN HORN.
